UNITED STATES PATENT OFFICE

2,424,280

GARMENT HANGER

Carl Lurtz, Brooklyn, N. Y.

Application May 7, 1943, Serial No. 486,067

8 Claims. (Cl. 223—91)

1

This invention relates to garment hangers, and more particularly to that type of construction having a mechanical arrangement whereby a garment, such as a skirt or pair of trousers, may be held in position by a compressing action of certain lever-elements in the mechanical arrangement.

The general construction of the device disclosed in this application comprises two arms pivotally interconnected at one end so that one arm may turn upon the other; while the respective free ends of the arms are adapted to hold compressed thereinbetween a garment or some other piece of material, with aid of a locking device of novel construction.

Analogous devices, heretofore constructed on the basis of the fundamental principles above premised, usually embody some permanently connected operating means whereby the two arms may be set together or closed for obtaining leverage; such operating means as employed in the prior art may be in the form of a lever-spring, a screw device, a pivoted lever-link, a slidable collar, or some similar device operatively connected to enable leverage to be exerted on the arms for moving them so that they may be set together or closed. As a general rule, the said means or locking device is connected to one or both arms in such manner that angular motion therein may be effected within limits of a comparatively small angle; and the locking device usually moves co-extensively with the arms while they are being operated. Such impeded and restricted angular motion in the arms is in many cases disadvantageous, because it may render inconvenient the positioning of a piece of material between the clamping elements of the arms.

One of the objects of the present invention is, therefore, the provision of means whereby the above noted disadvantages may be eliminated in a simple and effective manner. This end is achieved with a construction embodying two pivotally interconnected arms operatively associated with a locking device; but the characteristic features of the locking device are to enable the device to be moved at will to operative or to inoperative position; and with co-operation of co-active means embodied with the arms, it affords one of the arms to be swung away freely beyond the limited angle within which gripping action between the free ends of the arms may be effected with aid of the locking device when disposed in operative position.

Another object of the invention resides in the

2

particular arrangement of the means co-active with the detachable locking device; the said means comprises supplementary lever-elements disposed on each arm in such position relative to the path of angular motion of the arms in relationship with respect to each other that when one arm is moved angularly towards the other over a certain angle of limited degree, then the supplementary lever-elements are moved so that the distance between them increases gradually, reaching a maximum when the respective free ends of the arms come in contact with each other. An additional distinguishing feature of said co-active means is to enable the supplementary lever-elements to be carried beyond a certain point of closest approach while the free end of one arm is moved beyond a definite point in its arcuate path from the other arm.

A further object of the present invention is to provide such a construction that at least one of the two pivotally interconnected arms is enabled to support an additional garment, such as a coat, which, with aid of the other arm may be held in position to prevent said additional garment from becoming displaced on the first mentioned supporting arm.

A still further object of the invention is the provision of means to enable the gripping elements of the device to be shifted at will to various stationary positions within definite limits, so that gripping action between the pivotally interconnected arms may be effected at points selectively located a definite distance apart on the left and right-hand side of each of said arms.

And a still further object of the invention is to provide a pivotal connection for the two arms of such construction that a minimum of parts and assembly operations are required for making such pivotal connection.

With the foregoing and other purposes in view, the invention consists in the novel features of construction, combination and arrangement of parts as will be hereinafter more fully described, illustrated in the accompanying drawings and the appended claims.

In the drawings, wherein like characters denote corresponding parts in the different views:

Fig. 1 is a plan view of the garment hanger as seen from the front, showing the holding arms closed together, and the locking device in operative position;

Fig. 2 is a side-view of Fig. 1, seen from the left-hand side;

Fig. 3 is a similar side-view of the device, show-

ing the two arms swung apart, while the locking device is out of operative position;

Fig. 4 is a fragmentary detail view of the gripping members of the garment hanger, on a plan indicated by the broken line A—A of Fig. 1;

Fig. 5 is a side-view of a modification, showing certain detailed constructional features pertaining to the pivotal connection of the holding arms;

Fig. 6 is a plan view of another modification, embodying a coat-supporting member shown extending from the shaft on the front-arm of the device;

Fig. 7 is a fragmentary view, taken approximately on the broken line C—C of Fig. 6;

Fig. 8 is a further modification, showing the rear-arm of the device formed so that it may serve for the support of an additional garment, and also to serve for the support of adjustable gripping elements;

Fig. 9 is a cross-sectional view of one of the adjustable gripping elements, taken on line D—D of Fig. 8;

Fig. 10 is a plan view of still another modification, showing the device adapted for the support of either a coat or a pair of trousers or both pieces of garment; a section of a coat is indicated in dotted lines to show how this garment may be supported with aid of the front and rear-arm;

Fig. 11 is a fragmentary view of the device of Fig. 10, on a plan indicated by the broken line E—E, showing detailed constructional features of those parts whereby the two arms are pivotally interconnected, the several parts being illustrated in unassembled position.

While some or all of the present improvements are capable of embodiment in devices other than garment hangers, it is in the latter that said improvements are particularly adapted for beneficial incorporation, and for this reason a device adapted for the support of garments has been chosen for purposes of illustrating said improvements.

The device as exemplified in the drawing, Figures 1, 2 and 3, comprises two pivotally interconnected arms; the rear-arm being indicated by reference character 8A, and the front-arm by the character 8B, these arms may also be termed first and second arm. When the rear and front-arm are not locked together by means of a locking device, such as a wedge or some similar locking means, then the front-arm 8B is entirely free to be swung away from the rear-arm over an angle greater in degree than the limited angle within which the arms are adapted to effect gripping operation between their respective free ends. For attaining such gripping action effectively, each arm is shown provided at its free end with a transverse holding member 9 and 10, respectively, arranged in parallelism, and made of a suitable length to enable a garment 11, indicated in dotted lines, to be securely held in position. The mid-section of each of said holding members is reduced in thickness over a substantial length, as illustrated in Fig. 4; thus imparting a definite degree of flexibility to the holding members 9 and 10, serving to cause the opposing cheeks 12—13 to be held yieldably in pressure contact with the garment when the locking device is disposed in operative position to hold the arms together.

For pivotally interconnecting the two arms, there is shown in the drawing a pivot-support 14, forming an integral part of the rear arm 8A. The pivot-support 14 is provided with a trans-

verse hole (shown in broken lines in Fig. 1), or some other suitable form of shaft-bearing, for accommodation of the shaft-member 15, which forms part of the front-arm 8B.

5 The particular example illustrated in Fig. 1 through 4 is of such design that wood may serve well as material for the construction of all the parts of the device. When such material is chosen for fabrication of the garment hanger, then the 10 pivot assembly of the two arms may be made economically in the manner as exemplified in the drawing; this assembly involves the following progressive manufacturing operations: The shaft 15 is inserted axially into its bearing in the pivot-support 14, allowing the shaft to project on either side of the pivot-support. Thereafter, a permanent connection is made in some suitable manner between the projecting ends of the shaft 15 and the respective end-portions of the bifurcated end of the arm 8B. The outcut 16 of said bifurcated end is made of sufficient depth to enable the supplementary lever-element or edge 17 of the arm 8B to clear the forward projecting detent-member or nose 18, the latter forming a unit with the pivot-support 14, and may be 15 regarded as a supplementary lever-element on the rear-arm 8A. The operative part of the nose 18 is its contact-surface 19, which is shown extending from the lateral inner side of the rear-arm forwardly and beyond the lateral inner side of the front-arm 8B, i. e., at such time when the latter is disposed, relative to the rear-arm, within that particular angle within which gripping operation between the respective free ends of the two 20 arms may be effected, as will be more fully described hereinafter.

The operating element co-active with the wedge, and located at the base of the outcut 16 on the arm 8B, is the contact-face of the said edge 17, which, when the two arms are relatively close together, is disposed at a definite distance beneath the said contact-surface 19 of the nose 18. The arcuate path over which the contact-face of the edge 17 is carried, when the 25 front-arm 8B is swung away from or towards the rear-arm 8A, is shown by the broken lines 20 in Fig. 3. It will be noted that the said arcuate path is such, in relation to the disposition of the contact-surface 19, that the edge 17 gradually approaches the said contact-surface 19 while the arm 8B is swung away from the arm 8A over an initial limited angle, contained within the limits indicated by the broken lines 20A—20B. Now, the purpose of the afore related arrangement is to enable a locking device, such as a wedge 21 or similar blocking device to be effectively employed for urging and locking the two arms 8A and 8B together, so that a piece of material, when placed between the respective free 30 ends of the said arms, may be held securely in position thereby.

In Figs. 1 and 2, the wedge 21 is shown disposed in operative position, that is to say, in a position in which the wedge 21 and the said supplementary lever-elements of the arms co-act for locking the arms together. This end is achieved as best shown in Fig. 2, where the wedge 21 is shown with its upper contact-face held in engagement with the contact-surface 19 of the nose 25 18, while a portion of the opposite face of the said wedge is held in engagement with the contact-face of the edge 17 at the base of the outcut 16. It will be apparent, the more the wedge 21 is pulled outwardly, from its operative position 30 shown in Fig. 2, the more will the arm 8B be

allowed to recede angularly from the arm 8A, until, finally, the distance between the contact-surface 19 and the said contact-face of the edge 17 becomes too small to permit the wedge 21 to occupy the intervening space between the said contact-surface and the said contact-face of the first and second arm, respectively. After the wedge is thus moved from operative to inoperative position, it affords one arm to turn freely upon the other over a comparatively large angle, limited only by the upper end-section of the pivot-support 14, which end-section lies in the path of the edge 17. The wide angle over which the arm 8B may thus be moved relative to the rear-arm 8A is of considerable advantage, because this enables a garment or some other piece of material to be placed in position between the two parallel holding members 9 and 10 with maximum convenience.

In practice, when a garment is desired to be placed between the gripping elements of the device, the latter may be put, rear-side down, on a table or similar support. This will leave both hands free for placing the garment properly in position on the cheeks 12 of the transverse holding member 9; provided, of course, that the front-arm 8B is first swung away from the rear-arm 8A to the desired distance. Subsequently, the arm 8B is moved back to bring the holding member 10 with its cheeks 13 in pressure contact with the garment, and then the wedge 21 is pushed into the intervening space between the contact-surface 19 and the edge 17 so as to prevent the arms from moving apart. When the wedge is thus pushed into holding position, its drag on the edge 17 of the arm 8B causes both arms to be flexed toward one another to a small degree, and the resulting spring pressure is transmitted to the cheeks of the holding members 9 and 10; while part of the counteractive force or reflex action of the arms causes pressure to be exerted on the upper and lower side of the wedge 21, thus holding it in frictional engagement with the co-acting detent-elements of the device.

It will therefore be understood that the said wedge with its co-active parts is capable to serve as a device for urging the arms toward one another over a distance of relatively small degree. However, the wedge is principally adapted to function as a motion-inhibiting device.

By virtue of the resiliency of the holding members 9 and 10, coupled with the additional small resiliency inherent in the longitudinal sections of the rear and front-arm, it permits frictional resistance on the wedge to be relieved almost completely if the front and rear-arm are pressed together, thus allowing the wedge to be removed with great ease.

In the device of Fig. 1, the means whereby the garment hanger may be pendently connected to a stationary support, is shown in the form of a cord 22, which is permanently fixed at one end to the upper end-section of the pivot-support 14. On the other free end of the cord 22 is formed a loop 23, which is adapted to be detachably hooked on the projection 24 so that the garment hanger may be connected to any type of stationary support designed for such purpose. This cord-arrangement is intended to take the place of the usual wire-hook, in case the use of the latter is for some reason or other not preferred. The said projection 24 is shown formed from a separate piece of material, which is glued or secured in some other suitable manner in a slot made into the head-piece of the pivot-support 14. At the bottom of said slot is held squeezed down a part of

the cord 22, the remaining end-part of which extends through the hole 25 (Fig. 1) of the pivot-support 14 to the outside thereof, where the extremity of the cord-section 26 is fixed to the heavy end of the wedge 21. All the various features of this particular cord-suspension device will be described with greater detail in a separate application.

In Fig. 5, is illustrated a modification of the device; this modification is in its constructional and functional characteristics nearly the same as the first described example. The various parts of the device of Fig. 5 will, therefore, be pointed out only briefly in the following paragraph, after which the distinguishing features of the modification will be described in detail.

The rear-arm 8C with its holding member 9B, and the front-arm 8D with its holding member 10B, are pivotally interconnected so that operation therein may be effected in like manner as in the device of Fig. 1. The detent-element or nose of the arm 8D is indicated by the reference character 18B, and the detent-element of the arm 8D is indicated by the reference character 17B; between these elements is shown in operative position the wedge 21, which is adapted to perform its specific function as hereinbefore described.

The device of Fig. 5 is designed so that the front and rear-arm, plus the appended parts thereof, may be die-cast economically in two separate units, ready for assembly. Thus, the garment hanger, embodying the present invention, may be fabricated with a minimum of hand-work from suitable plastic material or from metal. In the event a plastic material of relatively low strength is used in the construction of the device, then it may be desirable to reinforce those parts of the arms where the strain of leverage is greatest. This end may be achieved by providing rib-sections as indicated in the drawing by reference character 27B and 28B; the rib-sections 27B are formed, respectively, on the left and right-hand side of the rear-arm 8C, and the rib-sections 28B are formed on the left and right-hand side of the front-arm 8D; in Fig. 5, the left-hand side of the device is brought to view.

The journal-bearing of the pivot-support 14B is made in the form of a semi-circular transverse groove 29B, open at the front-face of the said pivot-support, so that the shaft-section 15B of the arm 8D may be inserted from a lateral direction into the said bearing 29B; thus eliminating the necessity of connecting the front-arm to its shaft separately, like in the construction of the device of Fig. 1. The block 30, attached to the pivot-support 14B by a screw 31 or some other form of securing device, is adapted to cover the lateral front-opening of the journal-bearing 29B, so as to prevent the shaft 15B with its arm 8D to be moved out of assembled position.

The hook 22B is shown forming a fixed part of the rear-unit, which includes the pivot-support 14B, the arm 8C and its transverse holding member 9B.

In the modification shown in Figs. 6 and 7, the journal bearing 29C (Fig. 7) is open at the rear-side of the pivot-support 14C, and the upper part of the rear-arm 8C is adapted to retain the shaft-member 15C of the front-arm 8D in assembled position. The supplementary member, adapted for the support of an additional garment, such as a coat, is shown embodied in the form of two curved branches 33A and 33B, extending respectively to the left and right of the pivot-support 14C, which carries the metallic hook 22D. As

indicated in dotted lines in Fig. 6, either one or both free ends 33C of the supplementary member 33A—33B may serve to lend additional support to another garment, such as a skirt 11A, while the latter is being held at certain other points in position between the free ends of the front and rear-arm of the device with co-operation of the wedge 21.

In the device of Fig. 8, the rear-arm 8E, having the hook 22C, is made of a form adapted for the support of an additional garment. To the respective free end-sections of the arm 8E is fixed the transverse rod 9C, carrying the spaced-apart gripping elements 34A and 34B so that a second garment may be held in position between the cheeks 12B of the gripping elements 34A—34B and the opposing cheeks 13A of the transverse holding member 10B on the front-arm 8F, when the two pivotally interconnected arms are held closed together by means of the wedge 21. The pivot-support 14D, accommodating the shaft 15D of the front-arm 8F, is connected to the rear-arm 8E at its mid-section. The two separate gripping elements 34A and 34B are supported so that they may severally be shifted to different stationary positions on the rod 9C. Thus, a garment may be clamped in position at points within wider or narrower limits apart, depending to what particular position the gripping elements 34A and 34B are shifted in relationship with respect to each other. Each of the said gripping elements is shown having a nail or similar projection 36 made to project loosely into a slot 35 on the rod 9C (Fig. 9) to prevent rotative motion in the gripping elements. Similar elements may, of course, be adjustably mounted in some suitable manner on the transverse holding member 10B of the front-arm 8F, in which case the gripping elements of the rear-arm 8E may be replaced by stationary gripping elements of the desired length.

Before proceeding with the description of Fig. 10, it is important to bear in mind that whenever one of the two pivotally interconnected arms of the device embodies a coat-supporting member, it enables the other arm to interfunction in such a manner that a certain part of the coat, which does not rest on the coat-supporting member, may be clamped in position between the free ends of the two arms, thus holding the coat securely in position on its supporting member so that the garment cannot be shifted from its original position as long as the two arms are held locked together. It will, of course, be understood that with incorporation of a coat-supporting member, the device is adapted for the support of a pair of trousers or a coat, or both garments if desired.

The manner of supporting a coat with aid of the present invention as related in the preceding paragraph, is best illustrated in Fig. 10. The coat 11B is shown in dotted lines, supported by the coat-supporting member 31 which forms part of the rear-arm 8G; the rear-arm includes the pivot-support 14G and the transverse rod 10D on which the two spaced-apart gripping elements 12C are disposed opposite the spaced-apart gripping elements 13C, arranged on the free end of the front-arm 8H. The gripping elements 13C are shown made of fibrous material (Fig. 11), such as felt or some similar material whereby effective gripping action may be obtained with a minimum requirement of contact-pressure for holding the garment in position. The particular arrangement of the pivotal connection for the

two gripping arms enables those elements whereby the coat 11B may be clamped in position to be located somewhere on the front-face of the rear-arm, and at a certain distance away from that specific part of the arm on which the coat is adapted to rest. As a result, the respective gripping elements of the front and rear-arm, as shown in the drawing, are well adapted for holding the collar-part of the garment clamped in position so that the coat cannot shift on its supporting member 31 as long as the wedge 21B holds the two arms closed together.

In Fig. 11 are shown constructional details of the device whereby the two arms may be pivotally interconnected in a simple and economical manner. The pivot-support 14G is shown provided on its oppositely lying left and right-hand face with a depression 38A and 38B, respectively, adapted to form by its edge 39 a shaft-bearing for the spaced-apart shaft-elements 40 of the front-arm 8H. If the front-arm is made of wood, then it is convenient to employ round fiber washers for the shaft-elements 40. Each of these washers is provided with a hole of suitable dimension to accommodate therein, respectively, the shouldered shaft-section 41, formed from the arm at the upper left and right-hand side of its round outcut 16B (see Fig. 10); the said outcut further embodies the operating edge 17B which is adapted to receive the lower side of the wedge 21B when the latter is disposed in operative position as shown in Fig. 10. Now, when the shaft-elements 40 are in position on the arm 8H, as indicated in Fig. 11, the next assembly operation is performed by inserting the shaft-elements 40, while on the arm 8H, into the depressions 38A—38B from the rear-side of the pivot-support where said depressions are open. Subsequently, the pivot-support 14G is connected to the rear-arm 8G, and after this final connection is made, the rear-opening of each of said bearing-depressions is blocked by a portion of the rear-arm 8G so that the two arms remain securely hinged together. In the drawing, the pivot-support 14G is shown provided with a tenon 42 at its rear-side, adapted to fit into the mortise 43 of the rear-arm 8G; thus providing a simple form of connecting joint between the pivot-support and the rear-arm. It will, of course, be apparent that the pivot-support 14G may be connected in some other suitable manner to its arm. The upper end-section of the pivot-support 14G is shown provided with a hook 24B. In Fig. 10 is shown in dotted lines a stationary support, in the form of a rod 44, adapted for holding the garment hanger suspended.

Without further description it is thought that the features and advantages of the herein described invention will be readily apparent to those skilled in the art, and it will of course be understood that changes in the form, proportion and details of construction may be resorted to, without departing from the spirit of the invention and scope of the appended claims.

I claim:

1. In a garment hanger, means for connecting it in a pendent position to a stationary support, a first and second angularly movable arm pivotally interconnected at one end to enable a piece of material to be held between the free ends of the arms when the latter are held closed together; supplementary lever-elements having operating contact-faces arranged respectively on the first and second arm and movable co-extensively therewith, a wedge adapted to engage each of said

contact-faces for urging the arms together with movement of the wedge in a definite direction over a limited path, and an instrumentality co-active between said supplementary lever-elements and the wedge to afford the latter to be moved completely out of its limited path in a direction away from the pivotal interconnection of the arms.

2. A garment hanger, comprising a pair of arms pivotally interconnected at one end to enable the free end of one arm to be swung away or toward the free end of the other arm, each of said arms having lever-devices 17—18 normally disposed at spaced relation with respect to each other, a wedge having a first and second contact-surface adapted to operate within a limited path for holding the two arms together with cooperation of said lever-devices while in pressure-contact therewith to enable a piece of material to be held between the free ends of the arms, and means co-active between said lever-devices and the wedge for guiding the movement of the latter relative to the arms; said means including contact-elements on one of said lever-devices distributed over an area of definite extent to enable the first contact-surface of the wedge to come into pressure-engagement within its limited path of movement with said one lever-device at points to inhibit angular movement of the wedge on the plane of angular movement of the arm and lever-device having said contact-elements, at a time when the other lever-device is in pressure-contact with the second contact-surface of the wedge.

3. In a garment hanger, a first and second clamping-member normally disposed opposite one another, an extension on each clamping member including a device for holding said extensions pivotally interconnected to enable the first clamping-member to be moved over a limited angle toward and away from the second clamping-member, a lever-device 18 having a substantially flat contact-face 19 on one of said extensions, another lever-device 17 having contact-elements on the other extension; the arrangement of the lever-devices being to enable the contact-elements of one lever-device to be carried closer to or farther away from the flat contact-face of the other lever-device depending on the direction of movement of the clamping members relative one to another, and a detachable wedge having contact-elements on one side adapted to engage the flat contact-face 19 of said lever-device to enable the movement of the wedge to be guided in a linear direction while the contact-elements of the other lever-device engage the wedge.

4. In a garment hanger, in combination, a first and second arm pivotally interconnected at one end to enable a garment to be held in position between the respective free ends of the arms when locked together, a locking device adapted for locking the arms together in position for effecting compressing action between opposing free ends of the arms, and a member on at least one arm extending therefrom over a substantial distance to the left and right, the said member being arranged to clear the respective free ends of the arms and also the locking device thereof to swing coextensively with said arm on a common fulcrum therewith and to enable an additional garment to be supported by said member.

5. A garment hanger comprising means for connecting it in a pendent position to a stationary support, a first and second arm pivotally interconnected at one end to enable one arm to swing freely upon the other over a limited angle,

a gripping member arranged horizontally on the free end of each arm for holding compressed therebetween certain parts of a garment while the two arms are closed together, a detachably connected locking device adapted for holding the two arms closed together when the locking device is disposed in operative position, and an additional supporting member embodied with at least one of said pivotally interconnected arms; 5 said additional member including two branches extending respectively over a substantial distance to the left and right from the pivotal connection of the arms and curving downwardly to cause the free end of each branch to be disposed in proximity of the horizontally arranged gripping members to enable the garment therebetween to be additionally supported at the left and right-hand side, respectively, by the free end-section of each of said branch.

6. In a garment hanger, a first and second arm pivotally interconnected at one end to enable the free end of one arm to describe an arc in approaching the other, a transverse holding member on the free end of each arm, said holding members being arranged in parallelism with themselves, a plurality of gripping elements disposed at spaced relation with respect to one another on at least one of said holding members, a locking device embodied with the arms adapted for locking them together to afford clamping action between the opposing gripping elements of the arms to be effected, and means co-active between the holding member of at least one arm and at least one gripping element thereof to enable the latter to be shifted at will within definite limits toward or away from the next gripping element on the same holding member, affording clamping action to be effected between at least two separated points located anywhere within the limits determined by the position of the shiftable gripping element relative to other gripping elements on said holding members.

7. In a garment hanger, in combination, a first and second arm pivotally interconnected at one end to enable the free end of one arm to be swung away or toward the free end of the other arm, a detachable locking device co-operable with the first and second arm adapted for locking the arms together when disposed one relative to the other within the limits of a certain angle within which a garment may be held in position between the opposing free ends of the said arms, a shaft-support on one end of the first arm, said shaft-support having a transverse groove of substantial depth adapted to form a journal-bearing, a shaft-member on one end of the second arm adapted for accommodation in said groove and insertable through the lateral opening thereof, and a block connected to the shaft-support for covering at least part of said lateral opening of the groove to enable the shaft-member to be retained in operative position.

8. A clamping mechanism, comprising a first and second arm pivotally interconnected at one end to enable the free end of one arm to describe an arc in approaching the other, means on the free end of each arm for holding therebetween in position a part of material, a locking device embodied with the clamping mechanism adapted for at will closing the first and second arm together, a pivot-support embodied with the first arm but separately connected thereto, said pivot-support including two oppositely lying sides each of which having a depression to form bearing elements open at the rear-side of the pivot-sup-

11

port, spaced-apart shaft-elements on the second arm adapted for accommodation in said depressions by insertion of the shaft-elements through the respective rear-side openings of said depressions, and means on the first arm to retain the shaft-elements of the second arm in operative position on said bearing-elements when the pivot-support is permanently secured to the first arm.

Certificate of Correction

Patent No. 2,424,280.

July 22, 1947.

CARL LURTZ

It is hereby certified that error appears in the printed specification of the above numbered patent requiring correction as follows: Column 9, lines 67 to 69 inclusive, claim 4, strike out "swing coextensively with said arm on a common fulcrum therewith and to" and insert the same in line 66, same claim, before the word "clear"; and that the said Letters Patent should be read with this correction therein that the same may conform to the record of the case in the Patent Office.

Signed and sealed this 30th day of September, A. D. 1947.

[SEAL]

THOMAS F. MURPHY,
Assistant Commissioner of Patents.
